FROST INDICATOR FOR REFRIGERATORS

Richard J. Carberry, Erie, Pa., assignor to General Electric Company, a corporation of New York

Application December 21, 1950, Serial No. 201,971

7 Claims. (Cl. 116—114)

1

My invention relates to refrigerators and more particularly to frost indicators for refrigerator evaporators.

In many household refrigerators the food storage compartment is cooled by an evaporator whose surface is exposed to the air in the compartment. Consequently, moisture condenses from the air on the substantially cooler surface of the evaporator and collects thereon as frost. In order to maintain a satisfactory efficiency of the refrigerating apparatus, it is necessary to remove this frost from time to time, and hence it is desirable to call the user's attention to the thickness of frost collected thereon and particularly to call his attention to the presence on the evaporator of frost of a predetermined maximum thickness. In connection with horizontal, or full width, evaporators which extend substantially the full width of the food storage compartment and are covered by the evaporator door, it is difficult for the user to determine the amount of frost collected on the evaporator and hence easy for him to overlook the necessity for defrosting. Moreover, with this type of evaporator, the thickest blanket of frost usually collects on the rear wall of the evaporator where it is completely concealed from the user's view. By my invention I have provided an arrangement which clearly indicates to the user the thickness of frost collected on the evaporator and more particularly indicates the thickness of frost on the otherwise concealed rear wall of the evaporator. Moreover, the indicator is positioned so as to minimize the danger that the need for defrosting may be overlooked by the user.

It is an object of my invention to provide an improved arrangement for indicating a thickness of frost on a refrigerator evaporator.

It is another object of my invention to provide an improved arrangement for indicating the thickness of frost on a refrigerator evaporator each time the evaporator door is opened.

It is another object of my invention to provide an improved frost indicating arrangement particularly adapted for full width evaporators and including an element engaging the frost each time the evaporator door is opened to indicate the thickness of frost.

Further objects and advantages of my invention will become apparent as the following description proceeds and the features of novelty which characterize my invention will be pointed out with particularity in the claims annexed to and forming a part of this specification.

2

In carrying out the objects of my invention, I provide a slidable member positioned between the side wall of the evaporator and the side wall of the liner forming the food storage compartment. This member includes a laterally extending element adapted to engage the frost on the rear wall of the evaporator, and the member is biased forwardly by a spring so as to bring this element into engagement with the frost. A spring assembly is provided for biasing the evaporator door to its closed position and this spring assembly is arranged to engage the slidable member for moving the frost-engaging element away from the frost when the evaporator door is in its closed position. A rotatable tubular indicating element is arranged at the forward portion of the compartment and an elongated opening in this element is engaged by a spiral strip provided on the forward end of the slidable member so that movement of the slidable member is effective for rotating the indicating element by an amount depending upon the thickness of the frost on the evaporator. Suitable indicia are provided for indicating the thickness of frost or at least for indicating when an abnormal amount of frost has collected on the evaporator.

For a better understanding of my invention, reference may be had to the accompanying drawings in which Fig. 1 is a view of a portion of a refrigerator cabinet illustrating an embodiment of my invention; Fig. 2 is a plan view showing details of my invention; Fig. 3 is a side elevation view of the mechanism illustrated in Fig. 2; Fig. 4 is an enlarged view of the indicating element and its mounting; Fig. 5 is a front elevation taken along the line 5—5 in Fig. 4; Fig. 6 is a sectional view taken along the lines 6—6 in Fig. 4; and Fig. 7 is a view taken along the line 7—7 in Fig. 3.

Referring to Fig. 1, there is shown a refrigerator 1 including an inner liner 2 for defining a food storage compartment 3. The food storage compartment is cooled by an evaporator 4 which is of the horizontal, or full width type, extending substantially the full width of the food storage compartment 3. The access opening of the evaporator 4 is closed by a door 5. The door 5 is hinged, as indicated at 6, for movement about a horizontal axis. During normal operation, since the evaporator 4 is exposed to the air in the food storage compartment 3, moisture from the air condenses on the substantially cooler walls of the evaporator and collects thereon in the form of frost. This frost may eventually

reach a thickness sufficient to reduce materially the effectiveness of the evaporator. The frost build-up is particularly large along the rear wall of the evaporator. In order to indicate to the user the thickness of frost collected on the evaporator and particularly the relatively large thickness of frost which may collect on the concealed rear wall, an indicating arrangement illustrated in Figs. 2 and 3 is provided. This indicating arrangement includes a slidable member 7, which is disposed between the side wall 8 of the evaporator and the side wall 9 of the liner 2. This slidable member 7 includes a laterally extending portion or element 10 which is adapted to engage the frost on the rear wall 11 of the evaporator. The frost-engaging element 10 is formed of a generally U-shaped portion of the slidable member 7 so as to provide a relatively large area of contact with the frost, thereby minimizing the penetration of the frost by the frost-engaging element.

For slidably supporting the rear portion of the slidable member 7, a support 12 is provided at the rear portion of the side wall of the liner 2. This support 12 is secured to the side wall 9 by bolts 13 or other suitable fastening devices. The support 12 includes a slot or opening 14 within which the member 7 is slidably received. The rear portion of the member 7 is formed to include two parallel rods 15 and 16, both of which are received in spaced relationship within the opening 14. Details of the construction of the support 12 and of the mounting of the slidable member 7 therein are shown in Fig. 7. The broad idea of a frost indicator which includes a slidable member mounted adjacent the evaporator and having an element biased toward the frost on the evaporator and which includes means for connecting the slidable member and a directly visible rotatable indicating element for effecting rotation of the indicating element in accordance with the sliding movement of the member is not claimed in the present application but is described and claimed in my application Serial No. D. 88,047, filed concurrently with the present application and assigned to the same assignee.

At the forward portion of the compartment 3, there is provided a rotatable cylindrical indicating element 17. The indicating element 17 is rotatably mounted on a front support 18 which is secured to the front portion of the side wall 9 of the liner by screws 19 or other suitable fastening devices passing through-openings 19a. The support or bracket 18 is U-shaped, including spaced parallel sections 20 and 21. The sections 20 and 21 include openings 22 and 23, respectively, within which the indicating element 17 is rotatably mounted.

Details of construction of the indicating element 17 and the support 18 are shown in Figs. 4, 5 and 6. As there illustrated, the indicating element 17 includes a front cap or disc 24, a rear cap or disc 25, and an intermediate generally tubular section 26. The generally tubular intermediate section 26 is formed by two elongated spaced members 27 and 28 which are secured at their ends to the caps 24 and 25 and provide therebetween a space 29 for receiving the forward end of the slidable member 7. The indicating element 17 is held in fixed axial position with respect to the support 18 by a snap ring 30 received within a groove 30a in the cap 24. This ring 30 engages one face of the section 20 of the support 75

18 and a shoulder 31 formed on the cap 24 engages the opposite face.

In order to provide for rotation of the indicating element 17 coincident with horizontal or sliding longitudinal movement of the sliding member 7, the indicating element 17, and specifically its rear cap 25, is provided with an elongated opening 32 for receiving the forward end 33 of the slidable member 7, and this forward end 33 is twisted, as indicated at 34, into spiral form. Thus relative longitudinal movement between the slidable member 7 and the cap 25 of the indicating element 17 effects, through engagement of the spiral section or strip 34 with the elongated opening 32 a rotation of the indicating element 17. To minimize binding of the spiral strip 34 in the opening 32, the sides of the opening 32 are curved, as shown in Fig. 6. This relationship is employed for positioning the indicating element 17 so as to indicate to the user the frost condition on the evaporator. As mentioned previously, the laterally extending portion 10 of the slidable member 7 is arranged to engage the frost on the rear wall 11 of the evaporator, and the slidable member 7 is biased forwardly by a spring 35 to a position wherein the element 10 engages the frost. The spring 35 surrounds a portion of the rod 16 of the slidable member 7; one end of the spring engages a vertical leg 36 of the slidable member 7 and the other end engages the rear support 12, this latter end being received within a recess 37 in the rear support for assisting in positioning the spring. The amount of forward movement of the slidable member 7 under the bias of the spring 35, and hence the ultimate position of the rotatable indicating element 17, is determined by the thickness of the frost on the rear wall of the evaporator.

The evaporator door 5 is biased to the closed position illustrated by a spring assembly 38. This spring assembly 38 includes arm 39 having an opening 40 for receiving a pin 41 secured to the door 5 and a hook 42 received within an opening 43 in a bracket 44 secured by bolts 45 or other suitable fastening devices to the side wall of the liner. The spring assembly 38 further includes a spring 46 connected at its ends to the arm 39 in the hook 42.

The spring assembly 38 is utilized for maintaining the slidable member 7 in a rearward position wherein the frost-engaging element 10 is spaced from the frost on the rear wall of the evaporator whenever the evaporator door 5 is in its closed position. To effect this positioning of the slidable member 7, the spring assembly 38 further includes an upwardly extending element 41, and the slidable member 7 includes a cooperating depending element 48. As illustrated, for example, by the solid line position in Fig. 3, when the door 5 is in its closed position the depending element 48 is engaged by the upwardly extending element 41 and the slidable member 7 is held in a rearward position against the bias of the spring 35. The spring 46 is substantially stronger than the spring 35 and easily overcomes the bias of the spring 35. Whenever the evaporator door 5 is opened, the upwardly extending element 41 is moved forwardly to the dotted line position indicated at 49 out of engagement with the depending element 48, and under this condition the spring 35 moves the slidable member 7 forwardly. The amount of the forward movement of the slidable member 7 is dependent upon the thickness of the frost on the rear wall 11 of the evaporator, since the

forward movement of the slidable member 7 is limited by the engagement of the laterally extending portion 10 with the frost on the rear wall. The amount of the forward movement of the slidable member 7 in turn, through the actuation of the indicating element 17 by the spiral portion 34 of the slidable member 7, determines the amount of rotation of the indicating element 17. Suitable indicia are provided for utilizing this rotation of the indicating element 17 to indicate to the user the thickness of frost on the rear wall of the evaporator. As shown in Fig. 5, the section 20 of the support 18 is provided adjacent the opening 22 therein with suitable legends, for example "DEF" for indicating need for defrosting and "Normal" for indicating a thickness of frost below the predetermined maximum at which defrosting is essential. The indicating element 17 is provided with a pointer 50 arranged upon rotation of the indicating element 17 to point to various portions of the legend on the section 20 of the support 18. This pointer 50 may, as indicated in Fig. 4, be provided on a metal disc 51 secured to the front of the cap 24.

For providing a finished appearance, a filler strip 52 of plastic or other suitable material is disposed between the side wall 6 of the evaporator and the side wall 9 of the liner. This filler strip 52 is secured to a flange 53 on the front of the evaporator by screws or other suitable fastening devices (not shown) and a gasket 54 adapted to be engaged by the door 5 overlaps the inner edge of the filler strip 52. The filler strip 52 includes an opening 55 for receiving the indicating element 17 and the section 20 of the support 18 and with a second opening 56 through which the arm 39 of the spring assembly 38 passes.

The operation of the frost indicating mechanism is as follows. When the door 5 is in its closed position, as biased by the spring assembly 38, the upwardly extending element 47 engages the depending element 48 and moves the slidable member 7 to the rearward position indicated by solid lines wherein the frost-engaging portion 10 thereof is spaced from the frost on the rear wall 11 of the evaporator. Whenever the evaporator door 5 is moved to its open position, the upwardly extending element 47 moves away from the depending element 48 allowing the bias exerted by the spring 35 to effect a forward movement of the slidable member 7. The amount of this forward movement is determined by the thickness of the frost on the rear wall of the evaporator and by the engagement of the element 10 therewith. During forward longitudinal movement of the slidable member 7, the indicating element 17 is rotated because of the relative movement between the spiral section 34 of the slidable member and the elongated opening 32 in the disc 25 of the indicating element 17. The amount of rotation is, of course, determined by the amount of the longitudinal movement of the slidable member 7 and hence the final position of the indicating element 17 and of the pointer 50 thereon is determined by the thickness of frost on the evaporator. Thus, where there is substantially no frost on the evaporator and when the slidable member 7 moves to the dotted line position indicated in Figs. 2 and 3, there is substantial clockwise rotation of the indicating element, as viewed from the front end thereof, effected by the spiral section 34 and the indicating element occupies an ultimate position shown in Fig. 5 wherein the pointer 50 is directed well down in the normal range, indi-

cating little or no frost on the evaporator. As the frost builds up on the rear wall of the evaporator and hence as the forward movement of the slidable member is limited to a lesser amount than that indicated by the dotted line position in Fig. 3, there is a smaller clockwise movement of the indicating element 17 and the pointer 50 will occupy a position approaching more closely to the defrosting range indicated by the legend on the section 20 of the support 18. Ultimately when the thickness of frost has reached a predetermined maximum at which defrosting is considered essential, there will be little forward movement of the slidable member 7 and hence little clockwise rotation of the indicating element 17 and the pointer 50 will point to the area indicated by "DEF," thereby indicating the need for defrosting. As an alternative to the defrost and normal legends illustrated, it will be appreciated that the section 20 of the support 18 could be marked with graduations whereby the pointer would indicate directly the thickness of frost on the rear wall of the evaporator.

While I have shown and described a specific embodiment of my invention, I do not desire my invention to be limited to the particular construction shown and described and I intend by the appended claims to cover all modifications within the spirit and scope of my invention.

What I claim as new and desire to secure by Letters Patent of the United States is:

1. A refrigerator comprising a liner defining a food storage compartment, an evaporator upon which frost collects disposed in said compartment, a slidable member mounted adjacent said evaporator, said member including an element for engaging the frost collected on said evaporator, means for biasing said member toward a position where said element engages said frost, a rotatable indicating element mounted at the forward portion of said compartment, said indicating element having an opening of elongated cross section therein, said member including a spiral strip at its forward end received in said opening whereby sliding movement of said member effects rotation of said indicating element, and means for normally maintaining said frost-engaging element spaced from said frost against the bias of said biasing means.

2. A refrigerator comprising a liner defining a food storage compartment, an evaporator upon which frost collects disposed in said compartment, a slidable member mounted adjacent said evaporator, said member including an element for engaging the frost collected on said evaporator, means for biasing said member toward a position where said element engages said frost, a rotatable indicating element mounted at the forward portion of said compartment, said element including an elongated tubular section, a first cap secured to one end of said tubular section and having an opening of elongated cross section therein, a second cap secured to the other end of said tubular section and having an indicating pointer thereon, said member including a spiral strip at its forward end received in said opening in said first cap whereby sliding movement of said member effects rotation of said indicating element, and means for normally maintaining said frost-engaging element spaced from said frost against the bias of said biasing means.

3. A refrigerator comprising a liner defining a food storage compartment, said liner including a side wall and a rear wall, an evaporator upon which frost collects disposed in said compartment,

said evaporator including a side wall spaced from the side wall of said liner and a rear wall spaced from the rear wall of said liner, a slideable member disposed in the space between said side walls of said evaporator and said liner, said member including a laterally extending portion adapted to engage frost collected on said rear wall of said evaporator, means for biasing said member forwardly to a position where said laterally extending portion engages said frost, a rotatable indicating element mounted at the forward portion of said compartment, said indicating element having an opening of elongated cross section therein, said member including a spiral strip at its forward end received in said opening whereby sliding movement of said member effects rotation of said indicating element, and means for normally maintaining said frost-engaging element spaced from said frost against the bias of said biasing means.

4. A refrigerator comprising a liner defining a food storage compartment, an evaporator upon which frost collects disposed in said compartment, a slideable member mounted adjacent said evaporator, said member including an element for engaging the frost collected on said evaporator, means for biasing said member toward a position where said element engages said frost, a rotatable indicating element mounted on the forward portion of said compartment, said indicating element having an opening of elongated cross section therein, said member including a spiral strip at its forward end received in said opening whereby sliding movement of said member effects rotation of said indicating element, a door for said evaporator, and a spring assembly for biasing said door to its closed position, said spring assembly engaging said slideable member for moving said frost-engaging element away from said frost when said evaporator door is moved to its closed position.

5. A refrigerator comprising a liner defining a food storage compartment, said liner including a side wall and a rear wall, an evaporator upon which frost collects disposed in said compartment, said evaporator including a side wall spaced from the side wall of said liner and a rear wall spaced from the rear wall of said liner, a front support secured to the front portion of said side wall of said liner, a rear support secured to the rear portion of said side wall of said liner, a slideable member mounted on said rear support, an indicating element rotatably mounted on said front support, said slideable member including a laterally extending portion adapted to engage frost collected on said rear wall of said evaporator, a spring engaging said rear support and said member for biasing said member forwardly to a position where said laterally extending portion engages said frost, said indicating element having an opening of elongated cross section therein, said member including a spiral strip at its forward end received in said opening whereby sliding movement of said member effects rotation of said indicating element, and means for normally maintaining said frost-engaging element spaced from said frost against the bias of said biasing means.

6. A refrigerator, comprising a liner defining a food storage compartment, an evaporator upon which frost collects disposed in said compartment, a slideable member mounted adjacent said evaporator, said member including an element for engaging the frost collected on said evaporator, means for biasing said member toward a position where said element engages said frost, a rotatable indicating element mounted on the forward portion of said compartment, said indicating element having an opening of elongated cross section therein, said member including a spiral strip at its forward end received in said opening whereby sliding movement of said member effects rotation of said indicating element, a door for said evaporator, and a spring assembly for biasing said door to its closed position, said slideable member including a depending element, said spring assembly including an upwardly extending element for engaging said depending element to move said frost-engaging element of said slideable member away from said frost when said evaporator door is in its closed position.

7. A refrigerator comprising a liner defining a food storage compartment, said liner including a side wall and a rear wall, an evaporator upon which frost collects disposed in said compartment, said evaporator extending substantially the full width of said storage compartment and including a side wall spaced from the side wall of said liner and a rear wall spaced from the rear wall of said liner, a slideable member disposed in the space between said side walls of said evaporator and said liner, said member including a laterally extending portion adapted to engage frost collected on said rear wall of said evaporator, means for biasing said member forwardly to a position where said laterally extending portion engages said frost, a filler strip between said side wall of said evaporator and said side wall of said liner, said filler strip having an opening therein, a rotatable indicating element mounted at the forward portion of said compartment and extending through said opening in said filler strip, said indicating element having an opening of elongated cross section therein, said slideable member including a spiral strip at its forward end received in said opening whereby sliding movement of said member effects rotation of said indicating element, said indicating element including a pointer on its front face, means adjacent said opening having indicia thereon whereby the position of said pointer indicates the frost condition on said rear wall of said evaporator, and means for normally maintaining said frost-engaging element spaced from said frost against the bias of said biasing means.
